(57) **CLAIM**

The ornamental design for a cookware grip, as shown and described.

DESCRIPTION

FIG. 1 is a perspective view of a cookware grip showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken lines in FIGS. 1-7 represent portions of the cookware grip that form no part of the claimed design.

1 Claim, 4 Drawing Sheets(56)
